BRACKET FOR CONVERTING A PORTABLE POWER DRIVE INTO A PIPE MACHINE

James Lake, Jr., Brooklyn, N.Y., assignor to New York
Plumbers' Specialties Co., Inc., Bronx, N.Y., a corpora-
tion of New York

Filed Apr. 3, 1961, Ser. No. 64,580

Term of patent 14 years

(Cl. D54—13)

Fig. 1.

Fig. 2.

Fig. 3.

Fig. 4.

Fig. 5.

Fig. 6.

FIG. 1 is a front elevation of the new bracket for converting a portable power drive into a pipe machine.

FIG. 2 is a top plan view of the same.

FIG. 3 is a rear elevation of the bracket.

FIG. 4 is a bottom plan view; and

FIGS. 5 and 6, respectively, are right and left hand end views of the bracket.

I claim:

The ornamental design for bracket for converting a

portable power drive into a pipe machine, substantially as shown.
